UNITED STATES PATENT OFFICE.

ALPHONSO D. WASTE, OF GALESBURG, ILLINOIS.

FILE-BOX.

SPECIFICATION forming part of Letters Patent No. 337,903, dated March 16, 1886.

Application filed November 12, 1885. Serial No. 182,616. (No model.)

To all whom it may concern:

Be it known that I, ALPHONSO D. WASTE, of Galesburg, Knox county, Illinois, have invented certain Improvements in File-Boxes, of which the following is a specification.

My invention is an improved file box constructed as fully described hereinafter, the object of the same being to permit papers to be readily packed and extracted with facility, ⁵ separately or together.

In the drawing, the figure represents a perspective view looking from the rear of a file-box constructed in accordance with my invention.

15 A, B, B', and C represent, respectively, the bottom, two sides, and front end of a rectangular box or receptacle forming the body of the file-box. This receptacle is partially covered by strips *a b*, secured transversely ²⁰ across the top of the same, at or near each end, there being a notch, *c*, at the outer edge of the strip *b*, and a corresponding notch at the edge of the bottom *A*, for a purpose described hereinafter. An end cover, *F*, slides at the end of ²⁵ the receptacle in guides in the strip *b* and bottom *A*, and is provided with a spring-catch, *i*, (shown in dotted lines,) secured to its inner side and bearing against the edge of one of the sides, *B*, when the cover is closed. As the ³⁰ papers to be placed within the file are approximately the length of the same, (file-boxes of different sizes being generally used with papers of different lengths,) they are slightly curved or bent when inserted, so as to admit ³⁵ of their ends passing beneath the top strips, *a b*, of the receptacle, after which they can

assume a level position and lie smoothly within the box, and are securely retained by the overhanging strips *a b*.

Access can be had to the papers for removal ⁴⁰ at any time by withdrawing the cover *F*, and the notches *c* permit the ends of the papers to be easily grasped, so as to remove the entire mass or select any paper therefrom.

It will be obvious that the cover *F* may be ⁴⁵ hinged or otherwise movably secured to the box, and, if desired, may be provided with any suitable locking device.

I do not limit myself to the precise construction shown, as the same may be modified or ⁵⁰ changed without departing from my invention.

I claim—

1. A file-box, open at the top for the insertion of the papers, provided with overhanging ⁵⁵ strips *a b* and with a transversely-movable end cover *F*, substantially as and for the purpose set forth.

2. The combination, in a file-box having an open top and a notched bottom, of the top end ⁶⁰ strip *a* and the top end strip *b*, having the notch *c*, and transversely-movable end cover *F*, provided with a retaining device, substantially as and for the purpose described.

In testimony whereof I have signed my ⁶⁵ name to this specification in the presence of two subscribing witnesses.

ALPHONSO D. WASTE.
